UNITED STATES PATENT OFFICE.

STATES LEE LEBBY, OF CORNING, NEW YORK.

FOCUSING MEANS FOR LIGHT PROJECTORS.

Application filed September 15, 1922. Serial No. 588,402.

To all whom it may concern:

Be it known that I, STATES LEE LEBBY, a citizen of the United States of America, and a resident of Corning, New York, have 5 invented certain new and useful Improvements in Focusing Means for Light Projectors, of which the following is a specification.

This invention is an improvement in focusing means for light projectors.

The principal object of the invention is to provide an improved means for supporting and adjusting the light source of a light projector, having the advantages of 15 simplicity in design, economy in construction, ease in assembly and disassembly, and accuracy and simplicity in operation.

These and further objects of the invention will become more fully apparent as 20 the description proceeds.

In the drawings forming a part of this application—

Figure 1 is a front elevational view of a lamp equipped with the invention.

25 Figure 2 is a sectional view therethrough.

Figure 3 is a fragmental perspective view of the lamp and lower portion of the focusing device.

30 For convenience of illustration, I have shown the invention as applied to a spot light of the type commonly used on automobiles.

In the drawings, 5 indicates the lamp 35 casing, and 6 the reflector. The latter is retained in place by a ring 7 engaging its forward edge and affixed to the interior of the casing. The particular type of reflector shown is ordinarily manufactured with a 40 continuous beveled surface 8 just rearwardly of its forward edge. However, to effect the operation of the invention the beveled surface need not be continuous, it being sufficient if the portion opposite which 45 the focusing device is to be placed, be beveled.

The focusing device includes a base plate 9 on which the standard 10 is mounted. The standard carries the light source which 50 is illustrated as an incandescent lamp 11.

The base plate 9 is substantially triangular in shape, being wider at its inner end (which is nearest the reflector) than at its outer end. At its inner end the plate is cut 55 away as at 12 to form spaced ears 13, which engage between the beveled edge 8, and the

casing, and upon which the base plate will rock on an axis at right angles to the axis of the reflector, as the plate is moved inwardly or outwardly during the focusing 60 operation. Since the light source 11 is supported on the plate through the medium of the standard 10, pivotal movement of the plate inwardly or outwardly with respect to the axis of the lamp, will effect a movement of the light source toward or away 65 from the reflector.

A screw or threaded bolt 14 extends through an opening in the lamp casing 5, and through an opening in the base plate 70 9, and on this screw is arranged a spring 15, which bears against the inner surface of the base plate, and the tension of which is adjusted by means of an adjusting nut 16 mounted on the inner end of the screw. The 75 screw is preferably arranged between the standard 10 and the inner end of the base plate, and is equi-distant from the ears 13, so that the pressure exerted by the spring upon the base plate will be evenly distributed 80 between the two lateral halves of the base plate. An adjusting screw 17 is threaded through the casing and bears at its inner end against the under side of the base plate, and preferably near the outer 85 end thereof beneath the standard 10. The adjusting screw is alined with respect to the spring 15, longitudinally of the base plate, and hence by reason of the even distribution of the pressure of the spring over the base 90 plate, and the position of the adjusting screw, there will be no tendency for the base plate to rock laterally. The adjusting screw 17 is preferably provided with threads of such pitch that fine adjustment of the 95 base plate 9, can be secured. The adjusting screw operates upon the plate in opposition to the spring 15, and thus the tension of the spring will retain the plate in 100 adjusted position. While the maximum field of adjustment of the base plate 9 is comparatively small, the movements of the plate will be amplified, by reason of the length of the standard 10, so that the field of adjustment of the light source is 105 comparatively large.

The standard 10 is preferably made of a sheet of material doubled upon itself longitudinally, and having its lower end split along the bend for a short distance, the 110 sides of the standard being then out-turned to form flanges 18, which may be riveted

or soldered, or otherwise suitably secured to the base plate 9. The material forming the bend, for a suitable distance at the upper end of the standard, may be removed, and 5 the sides of the standard formed into a holder 19 in which a lamp socket 20 may be suitably mounted. From the contacts 21 of the socket, light wires may be led through the standard, i. e., between the lateral sides 10 thereof, and in desirable manner conducted to the source of current. The holder 19 formed at the upper part of the standard is 15 preferably arranged approximately in the axis of the reflector 6, and the standard 10 is inclined vertically to the proper degree, so that when the incandescent bulb 11 is placed in the socket, the filament of the bulb will be approximately in the focus of the reflector. In the particular type and size 20 of reflector used in this instance as an illustration, the standard 10 is slightly inclined toward the front of the lamp. It will be understood, of course, that the type of lamp, the proportions of the reflector and light 25 source, and the desired position of the light source, will determine in various instances, the position to be given the standard 10. In some instances, it might be arranged at right angles to the plate 9, and in others it might be inclined toward the rear of the lamp. By thus proportioning the parts so that the lamp when affixed in its socket will be approximately 30 adjusted, correct adjustment of the light source, toward or away from the reflector 35 can then be had by manipulating the adjusting screw 17.

The ring 7, which retains the reflector 6 in place is interrupted through that area 40 which is occupied by the base plate 9, so as to allow of the positioning of the pivotal ears 13 against the beveled face 8 of the reflector.

While the plate in the type illustrated is 45 shown as placed on the bottom of the lamp casing, the standard extending upwardly, it will be understood that the plate can be arranged at other points with respect to the circumference of the casing if so desired.

50 In assembling the device, the reflector 6 and retaining ring 7 having been secured in place in the lamp casing, the base plate carrying with it the standard and the light source, may be properly positioned in the 55 casing. The screw 14 may be then inserted through the aligned openings in the casing and the base plate, the spring 15 dropped in place upon the screw, and the adjusting screw 17 may be then turned into the casing, 60 and the wires having been connected with the source of current, and the current switched on, the adjusting screw may be turned to give the desired initial adjustment to the light source. The cover glass 22 may 65 then be mounted on the lamp.

The adjustment secured by this device is longitudinal adjustment of the light source substantially axially with respect to the reflector. Such adjustment will secure the desired angle of beam divergence, according to well known optical laws. The lateral axial position of the light source relative to the reflector is approximately correct by reason of the positioning of the holder 19 and its socket 20, and need not be changed. The longitudinal adjustment of the light source substantially along the axis, however, must be provided for in order to obtain the desired angle of beam divergence. 70

Having thus described the invention what is claimed is,—

1. The combination with a projector, of a light source carrying plate mounted for pivotal movement about an axis, an adjusting means operating against the plate in one direction, and spring means operating against the plate in the opposite direction and between the adjusting means and the axis of pivotal movement of the plate. 80

2. The combination with a projector casing and a reflector mounted therein and having a beveled surface forming an angle with the adjacent portion of the casing, of a base plate having pivotal ears engaging between the said beveled surface and said casing, a light source carried by the plate, and means for adjusting the plate, and retaining it in adjusted position. 90

3. The combination with a projector casing and a reflector mounted therein, of a base plate having spaced pivotal ears engaging against the reflector and casing, resilient means pressing the plate in one direction, adjusting means adapted to move the plate against the pressure of said resilient means, and a light source supported by the plate. 100

4. The combination with a projector casing, of a base plate, a light source-carrying standard mounted on the plate, spring means urging the plate against the casing, and an adjusting means operating against the plate in opposition to the spring means and to one side thereof, whereby the edge 110 of the base plate on the other side of the spring from the adjusting means will form a bearing contact with the casing. 115

5. In a focusing means for light projectors, a base plate having spaced bearing ears, a light-supporting standard mounted on the base plate, spring means substantially equi-distant from the bearing ears, and bearing on one side of the plate, and adjusting means beyond the spring means with respect to the bearing ears, and engaging the opposite side of the plate. 120

6. The combination with a projector casing and its light bulb, of means for supporting and focusing said bulb comprising a 130

standard carrying said bulb at its upper end and having its lower end resiliently pivoted to the casing on an axis at right angles to the axis of the projector, and
5 screw means threaded through the bottom of the projector casing and acting against said standard at a point remote from its pivot.

7. The combination with a projector casing, of a light carrying standard having a

base portion elongated in a direction parallel with the axis of the projector, and having a resilient pivoted connection with said casing at one end of said standard, and screw means passing through the casing and 15 acting vertically against said base at a point removed from its point of pivotal connection.

STATES LEE LEBBY.
